(57) CLAIM

I claim the ornamental design for stop lamp for automobile, as shown and described.

DESCRIPTION

The stop lamp for automobile is made from a molded synthetic resin and is mounted on the rear part of a back seat and functions to turn on and off at the same time as the break lamp.

FIG. 1 is a front perspective view of the stop lamp;

FIG. 2 is a front elevation view of the stop lamp;

FIG. 3 is a back elevation view of the stop lamp;

FIG. 4 is a left side plan view of the stop lamp, where the right side of the stop lamp is the mirror image identical to FIG. 4;

FIG. 5 is a top plan view of the stop lamp; and,

FIG. 6 is a bottom plan view of the stop lamp.
